CLAIM

The ornamental design for a swivel stick adapter, as shown and described.

DESCRIPTION

FIG. 1 is a top, front, right side perspective view of a swivel stick adapter showing our new design;

FIG. 2 is a bottom, back, left side perspective view thereof;

FIG. 3 is a front elevational view thereof, the back elevational view being a mirror image thereof;

FIG. 4 is a left side elevational view thereof, the right side elevational view being a mirror image thereof;

FIG. 5 is a top plan view; and,

FIG. 6 is a bottom plan view thereof.

The broken lines illustrate portions of the adapter that form no part of the claim.

1 Claim, 6 Drawing Sheets
